(57) **CLAIM**

The cap for a bottle for a liquid dispenser, as shown and described.

DESCRIPTION

FIG. 1 is a perspective view of a cap for a bottle for a liquid dispenser showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 shows a cap for a bottle for a liquid dispenser in an environment of use, the broken line showing of a bottle with contents, cover and dispenser forming no part of the claimed design.
